(57) **CLAIM**

The ornamental design for a pallet guard section, as shown and described.

DESCRIPTION

FIG. 1 is a front view of a pallet guard section showing our new design;

FIG. 2 is a top view of the pallet guard section of FIG. 1;
FIG. 3 is a back view of the pallet guard section of FIG. 1;
FIG. 4 is a bottom view of the pallet guard section of FIG. 3;

FIG. 5 is a left side view of FIG. 1;

FIG. 6 is a right side view of FIG. 1;

FIG. 7 is a perspective view of the pallet guard section of FIG. 1;

FIG. 8 is a perspective view of the pallet guard section of FIG. 1 showing a removable graphic panel partially removed;

FIG. 9 is a perspective view of the pallet guard section of FIG. 1 showing the extensible panel thereof partially extended showing the corner section separated from the rest of the pallet guard section;

FIG. 10 shows two pallet guard sections connected in series, one of the sections being shown in phantom without the corner section;

FIG. 11 shows two pallet guard sections, one in phantom and one partially extended with the two pallet guard sections turning a corner;

FIG. 12 shows a pallet guard section without the corner section and without the extensible portion;

FIG. 13 is a top view of FIG. 12;

FIG. 14 is a back view of FIG. 12;

FIG. 15 is a bottom view of FIG. 14;

FIG. 16 is a left side view of FIG. 12;

FIG. 17 is a right side view of FIG. 12; and,

FIG. 18 shows a pallet guard assembled from multiple pallet guard sections disposed around a pallet containing goods. The broken line showing of additional guard sections in the drawings is for illustrative purposes only and forms no part of the claimed design.
